UNITED STATES PATENT OFFICE.

HOWARD I. WOOD, OF SCHENECTADY, NEW YORK, ASSIGNOR TO GENERAL ELECTRIC COMPANY, A CORPORATION OF NEW YORK.

VAPOR ELECTRIC APPARATUS.

No. 831,401.

Specification of Letters Patent.

Patented Sept. 18, 1906.

Application filed March 31, 1904. Serial No. 200,884.

To all whom it may concern:

Be it known that I, HOWARD I. WOOD, a citizen of the United States, residing at Schenectady, in the county of Schenectady and State of New York, have invented certain new and useful Improvements in Vapor Electric Apparatus, of which the following is a specification.

My present invention comprises certain improvements in the construction of vapor electric apparatus. The features of novelty are pointed out with particularity in the appended claims.

The invention itself, however, will be better understood by reference to the following description, taken in connection with the accompanying drawing, which represents, by way of illustration, one of the numerous embodiments which my invention may assume in practice.

The particular embodiment which I have chosen to illustrate my invention is a mercury-vapor lamp. The exhausted glass envelop of the lamp consists, as shown, of a relatively long tube 1 of indefinite length, enlarged at the top to form a condensing-chamber 2. The lower electrode or cathode consists of a body of mercury 3 or other suitable material contained in the lower end of the tube. The upper electrode in the present instance is a small cylinder or tube 4, of carbon, artificial graphite, or the like. This electrode or anode is supported by a glass-incased wire 5, the upper end of which passes through the wall of the enlargement or condensing-chamber 2 and constitutes a leading-in conductor. The glass casing or tube 6 for the wire or rod 5 is at its top fused into the wall of the condensing-chamber and serves to hold the anode 4 rigidly at about the point where the main tube opens into the condensing-chamber.

An arm or projection 7, of glass, extends from the upper end of the tube 6. This projection incloses a wire 8, electrically connected to the conductor 5 and at its opposite end to a ring 9, of iron or the like. Within this ring 9 is loosely mounted a double-headed armature or core 10, the heads 11 and 12 of which serve to limit the motion of the core with respect to the ring.

A filament 13, of carbon or other suitable material, is supported at its upper end from

the core 12 and at its lower end dips into the mercury 3. This filament is held from lateral displacement by carbon-bushed guides 14, 15, and 16. A guide 14 is carried by the tube 6, as indicated. The other guides 15 and 16 are carried by a small glass tube 17, the upper end of which is fused into the upper wall of the condensing-chamber 2 and the lower end of which dips into the mercury 3. This tube 17 incloses a conductor 18, which extends throughout the length of the tube and projects at its upper end through the walls of the condensing-chamber 2 to form a leading-in conductor and at its lower end through the lower end of the tube 18 into the mercury 3. The glass-incased conductor 17 therefore furnishes an electrical connection to the mercury electrode 3. The arrangement shown, therefore, brings both the ingoing and outgoing electrodes of the lamp together at the top of the lamp, and so does away with the necessity for an external lead for the lamp extending outside of the lamp to the lower leading-in conductor at the lower end of the lamp, as has heretofore been the practice.

Instead of inclosing the internal lead or conductor 17 in a glass tube the conductor may of course, if desired, be insulated with some vitreous or other suitable insulating coating or enamel.

In order to start the lamp, a solenoid or similar magnetic device 19 is arranged so as when excited to exert an attractive influence on the core 10. The core 10 when the solenoid is excited is therefore lifted and carrying with it the filament 13 causes a withdrawal of the lower end of the filament from the mercury 3. The initial arc thus started extends practically instantaneously up the tube along the filament and terminates at the anode 4. The lamp is then in operation.

The solenoid 19 may be connected in series with the lamp, as shown, or, if desired, it may be excited in any other suitable way. In the drawing I have represented the solenoid as connected at one end to the conductor 5 from the anode and at the other end to the conducting-tip 20 of an attaching-plug. The screw-shell 21 of the attaching-plug is connected, as indicated, to the lead 18. The parts are secured in place by means of cement 22, constituting a filling between the con-

ducting parts of the attaching-plug and the projecting corrugated member 23 of the lamp-tube.

It is evident that numerous changes may be made in the embodiment of my invention without departing from the principle thereof, for which reason I do not wish to be limited to the exact details shown and described.

What I claim as new, and desire to secure by Letters Patent of the United States, is—

1. In a vapor electric apparatus, the combination of an exhausted envelop, electrodes at opposite ends of the envelop one at least of said electrodes being a fluid, and insulated

leads extending each from the inside of one end of the envelop, one lead dipping into the fluid electrode and the other connected to the other electrode.

2. A vapor-lamp having electrodes at opposite ends of the tube, one of said electrodes being a fluid, and leading-in wires for said electrodes passing through the same end of the lamp-tube, one of said leading-in wires being connected with a conductor dipping into the fluid electrode.

3. In a vapor electric apparatus, the combination of an exhausted envelop, an attaching-plug affording terminals for the lamp and secured to the lamp-envelop, a solenoid held

in place by said plug, an armature for said solenoid, and a starting device controlled by said armature.

4. In a vapor electric apparatus, the combination of an exhausted envelop provided with electrodes at opposite ends thereof and with leading-in conductors at the same end thereof, one of said electrodes being fluid, an attaching-plug secured to the lamp-envelop and having contact-surfaces electrically connected to the leading-in conductors, and an insulated electrical connection between the fluid electrode and one of the leading-in conductors.

5. In a vapor electric lamp, the combination of an exhausted envelop, electrodes therefor, a starting device consisting of a filament making a separable contact with one of said electrodes, an attaching-plug secured to the lamp-envelop, and affording terminals for the lamp, and electrical connections between the attaching-plug and the electrodes of the lamp.

In witness whereof I have hereunto set my hand this 29th day of March, 1904.

HOWARD I. WOOD.
